UNITED STATES PATENT OFFICE.

HERMAN B. SMITH, OF PLAINFIELD, NEW JERSEY, ASSIGNOR TO THE BABCOCK & WILCOX COMPANY, OF BAYONNE, NEW JERSEY, A CORPORATION OF NEW JERSEY.

WASTE-HEAT BOILER SYSTEM.

Application filed February 9, 1922 Serial No. 535,223.

My present invention relates to systems for operating steam boilers by the waste heat of industrial furnaces, and particularly contemplates an arrangement by which the heated gases supplied to such waste heat boilers may be supplemented by gases from a separately-fired furnace, preferably one using finely divided fuel, such as powdered coal, oil or gas.

Where the gases from industrial furnaces are utilized for the generation of steam, it sometimes occurs that, because of variations in the supply of such waste gases or variations in the demands for steam from such boilers, the two devices are out of balance, so that the desired amount of steam will not always be available. Heretofore, it had been the practice in such case to have an independent boiler and a furnace directly connected thereto which may be utilized to boost the steam supply when the latter falls off either because of increased demands, or because of lack of sufficient waste gases for that purpose. Such an arrangement, however, is inconvenient and expensive to operate.

By my present invention, I provide a separately-fired furnace which will supply additional heated gases as desired to the flue by which the waste gases from the industrial furnaces are carried to the waste heat boilers, so that a single boiler equipment will suffice for all purposes, while, at the same time, such boilers may be operated to give the desired amount of steam.

My invention will best be understood from the following description and accompanying drawings, in which Figure 1 is a plan view, more or less diagrammatic, of an installation of a plurality of waste heat boilers connected to a flue to which are supplied waste heat gases from a plurality of industrial furnaces and also from a separately-fired furnace; Fig. 2 is a section of Fig. 1 on the line 2-2 of Fig. 1; Fig. 3 is a section of Fig. 1 on the line 3-3 of Fig. 1, and Fig. 4 is a section on the line 4-4 of Fig. 1.

Like reference characters indicate like parts in the several views.

In the illustrative arrangement, the waste heat boilers 10 are connected to a distributing flue 11, to one end of which is connected a collecting flue 12, the flues 11 and 12 constituting, in effect, a single flue. A plurality of cement kilns 13 are connected to the

flue 12 by supplemental flues 14, each of the kilns being provided with a stack 15. Dampers 16 are provided to close entrance to the stacks 15, and dampers 17 are arranged to close the flues 14 from the flue 12. By this arrangement, the waste gases from the kilns 13 may either be directed to the stacks 15 or through the flues 14 to the flue 12 or both. Dampers 171 are provided between the flue 11 and each of the waste heat boilers 10, so that the passage of gases between the flue 11 and the several boilers 10 may be controlled.

At the end of the flue 12 is a furnace chamber 18 which, in the form illustrated, is provided with an oil burner 19 of any of the well-known forms, a damper 20 being arranged to cut off the furnace chamber 18 from the flue 12. In the illustrative form, dust pockets are provided beneath the various flues and the bottoms of these pockets are connected by suitable pipes through which the dust collected in these pockets may be carried to any desired point.

Ordinarily the system will be devised so that the waste gases from the industrial furnaces 13 will supply sufficient heat to the boilers 10 to provide the normal amount of steam required. If, however, through the cutting out of any one of the industrial furnaces, or through an increased demand for steam, the waste heat from these industrial furnaces is insufficient to give the required amount of steam, then the furnace 18 will be thrown into operation and the heated gases therefrom will enter the flue 12 and mingle with the gases from the industrial furnaces which are passing to the boilers 10. While the gases from the furnace 18 may be supplied at any point in the flue made up of the two parts 11 and 12, I preferably locate the separately-fired furnace so that the gases therefrom will enter the flue 11 at a point beyond the point of entrance of the gases from the industrial furnaces, or, in other words, I arrange the industrial furnace so that the gases therefrom will enter the flue at a point between the point of entrance of the heated gases from the furnace chamber 18 and the boilers. By this arrangement, the gases from the separately-fired furnace will be mingled with the gases from the industrial furnaces, and thereby provide a more uniform supply of heat to the boilers than

100
105

might be the case if the separately-fired furnace were located, say for instance, at the end of the distributing flue 11.

By using a furnace burning finely divided fuel, the necessity for maintaining a banked fire, as will be necessary if solid fuel were used, is avoided, and obviously the additional heat required can be supplied much more quickly than would be possible with such banked fires. When the separately-fired furnace 18 is not in use, the damper 20 may be closed to prevent the entrance of cold air into the flue 12.

By providing a plurality of industrial furnaces and a plurality of waste heat boilers connected thereto, with a single separately-fired furnace, a system of great flexibility is obtained with a minimum expense. In such an arrangement, any one of the boilers or any one of the industrial furnaces may be cut out and yet the system will not be unbalanced, because the separately-fired furnace can be operated so as to make up the deficiency due to such cutting out. For instance, if one of the industrial furnaces is cut out, then the separately-fired furnace can be put into commission to supply the necessary amount of heat to compensate for the amount of heat that would ordinarily be derived from such industrial

furnace. On the other hand, if one of the boilers is cut out, then it may be desirable to operate with the gas at a higher temperature than would be derived from the industrial furnace alone, in which case also, such additional heat may be obtained from the separately-fired furnace.

While I have illustrated my system in connection with cement kilns, it will be understood that any other form of industrial furnace may be used. Similarly, while I have illustrated the waste heat boiler of the type shown in the patent to Bell No. 1,332,284, it will be understood that any other form of waste heat boiler may be used.

I claim:—

In a system for utilizing the waste heat from industrial furnaces, a steam boiler, a separately-fired furnace adapted to burn finely divided fuel, a long flue connecting said furnace to said boiler and a plurality of industrial furnaces, each connected to said flue with the points of connection spaced along the flue, whereby the hot waste gases from all of the industrial furnaces are delivered to the flue between its connection to said boiler and its connection to said separately-fired furnace.

HERMAN B. SMITH.
